Philip Fawcett Rice Kennedy

UNITED STATES PATENT OFFICE.

JOHN L. MCATREE, OF NEW YORK, N. Y., ASSIGNEE, BY MESNE ASSIGNMENTS, TO SCOVILL MANUFACTURING COMPANY, OF WATERBURY, CONNECTICUT, A CORPORATION OF CONNECTICUT.

SIFTER TOP.

Application filed June 30, 1925. Serial No. 40,479.

This invention relates to certain improvements in sifter tops or covers for powder boxes, bottles and other containers for holding loose powder.

5 It is one object of the present invention to provide a sifter top structure of simple construction, the parts of which shall cooperate so as to produce essentially a powder tight structure between the top and the container 10 with which it is used, and in which the improved dispensing member is so held in position as to be practically powder tight except when exercising its powder dispensing function. It is a further object of the invention 15 to produce an improved operating member for actuating the dispensing member which is so arranged that there are no parts projecting sidewise from the top. A further object of the invention is to produce 20 an improved structure for assembling the top, the dispensing member, and the parts whereby the dispensing member is held in leak proof relation with the rest of the top.

With these and other objects not specifically referred to in view, the invention consists in certain novel parts, arrangements, and combinations which will be described in connection with the accompanying drawings and the novel features pointed out in the 30 claims hereunto annexed.

Referring to these drawings,—

Figure 1 is a side elevation, partly broken away and partly in section, showing the improved sifter mechanism as attached to a powder can;

Figure 2 is a plan view of the construction shown in Fig. 1;

Figure 3 is a view, partly broken away and partly in section, of the construction 40 shown in Fig. 1, the parts being in open or dispensing position, the section being taken on line 3—3 of Fig. 1;

Figure 4 is a sectional plan view taken on line 4—4 of Fig. 1, and

45 Figure 5 is a top view of the outer shell, the operating handle being omitted.

Referring now to these drawings, the container selected to illustrate the invention is a powder can marked 1, this can having a neck smaller than the body of the can. It will be understood, however, that the invention is not to be restricted to this form of container but is suitable for use with boxes,

such as vanity boxes, bottles or other containers used for dispensing loose powder. 55

The improved sifter top includes a single shell, which shell may, as in a vanity box, form the cover of the box, or it may, as in the particular construction shown, be smaller than the top of the box and be secured thereto in any suitable manner, as by being in turned over a bead 2 formed on the neck of the can. In the particular construction illustrated, this shell is provided with a depending flange 3, by which it may be secured to the can, and with a top 4 which is provided with a suitable number of distributing openings 5. Inside the shell there is provided a movable distributing member, this member being in the form of a thin flat disc of metal 6 or other suitable material marked 6 which is provided with corresponding distributing openings marked 7. This distributing plate is preferably somewhat smaller in diameter than the shell and is held in frictional engagement with the inner surface of the shell at or near its outer edges so that a close engagement is provided and one which makes the structure substantially proof against accidental leakage of powder. The means employed for holding the shell in position is, as is shown, a bowed spring 8, the ends of which engage the outer edges of the distributing disc at opposite points so that these edges are held in close frictional engagement with the top. 85

There is provided an actuator for manipulating the distributing disc to bring the openings 5, 7 in register, the disc having a rotary movement with respect to the top. 90 For simplicity in construction, the pivot for the actuator is utilized for holding the spring in place.

As shown, the actuator includes a handle 9 which is so proportioned as not to project laterally beyond the edges of the top. This handle is recessed to receive the end of a shank 10, this shank passing through a wing shaped slot 11 in the top 4 of the sifter and through a slot in the distributing disc 6. This shank at its lower end is split and the split ends are oppositely bent against the spring 8, as indicated at 12, 13 in Fig. 3, the parts thus being securely held in position in a simple manner. 100

105 The wing shaped slot 11 permits the rota-

tion of the operating handle within the desired limits, and in the best constructions stops 14, 15 are provided for holding the handle in the desired open or closed position, these stops being in the form of shallow depressions which receive a lug 16 formed on the bottom of the handle.

With the construction shown and described a very simple and efficient sifter top 10 has been provided. While the means shown for securing the parts together and the particular arrangement of the parts is a practical one, it will be understood that certain changes and variations may be made in the 15 structure without departing from the invention as defined in the appended claims.

What I claim is:

1. A sifter top for loose powder receptacles, comprising a single shell or cover 20 having dispensing orifices, a distributor disc having distributing orifices held in close frictional contact with the inner surface of the shell, a spring engaging the disc and pressing it into close frictional contact with the inner surface of the shell, a shank passing through the shell and disc centrally thereof and provided with a head and a low flat handle extending parallel with the top of the shell in close engagement therewith 25 and having a finger hold secured to the end of the shank and having frictional engagement with the top of the shell, and a co-operating recess and projection formed on the handle and the surface of the shell to 30 act as a stop for the handle in rotating the disc.

2. A sifter top for loose powder contain-

ers, comprising a shell or cover having distributing openings, a distributing disc in frictional contact with the shell, a spring 40 engaging the disc and pressing it in close contact with the shell, a handle for rotating the disc, and a pivot shank passing through the shell and disc and having its end slit and the slit portions oppositely 45 turned under the spring for holding it in place.

3. A sifter top for loose powder containers, comprising a shell or cover having distributing openings, a distributing disc in 50 frictional contact with the shell, a spring engaging the disc and pressing it in close contact with the shell, a low flat handle extending parallel with the top of the shell in close engagement therewith for rotating 55 the disc, and a squared pivot shank passing through the handle, shell, disc, and spring and having an integral part below the spring for holding the spring in place against the disc. 60

4. A sifter top for loose powder containers, comprising a shell or cover having distributing openings, a distributing disc in frictional contact with the shell, a spring 65 engaging the disc and pressing it in close contact with the shell, a handle for rotating the disc, and a pivot shank passing through the shell, disc, and spring and having its ends formed with oppositely disposed projections for holding the spring in place 70 against the disc.

In testimony whereof, I have hereunto set my hand.

JOHN L. McATREE.
